Specification for Design.

Patented May 27, 1913.

Application filed February 17, 1913. Serial No. 749,050. Term of patent 3½ years.

To all whom it may concern:

Be it known that I, ANTONI GRIBKO, a subject of Czar of Russia, residing at Hatfield, in the county of Hampshire and State of Massachusetts, have invented a new, original, and ornamental Design for Door-Knobs, of which the following is a specification, reference being had to the accompanying drawing, forming a part thereof.

In the drawing the figure is a perspective view of a door knob showing my design.

I claim:

The ornamental design for a door knob, as shown.

ANTONI GRIBKO.
